LIVE CENTER FOR LATHES, GRINDERS AND THE LIKE

Application filed February 18, 1931. Serial No. 516,650.

Our present invention has for its object the provision of a simple and highly efficient live center for lathes, grinders and the like, intended for general use but especially designed for use in connection with a dead center for holding a piston or other cylindrical body during the finishing thereof.

This invention, in part, is a division of our pending application filed March 21st, 1930, under Serial No. 437,741 and entitled "Piston turning and grinding machine".

Generally stated, the invention consists of the novel devices and combinations of devices hereinafter described in the claims.

In the accompanying drawing, which illustrates the invention, like characters indicate like parts throughout the several views.

Referring to the drawing:

Fig. 1 is a fragmentary front elevation of a lathe having the invention embodied therein, and also showing in the lathe a piston by means of broken lines;

Fig. 2 is a view principally in section taken on the line 2—2 of Fig. 1, on an enlarged scale;

Fig. 3 is the face view of the live center with some parts sectioned on the line 3—3 of Fig. 2; and

Fig. 4 is a fragmentary detail view with some parts sectioned on the line 4—4 of Fig. 3.

The invention is shown applied to a lathe especially designed for use in finishing pistons for internal combustion engines, and of the parts of the lathe, the numeral 5 indicates the bed, 6 the headstock, 7 the tailstock, 8 the driven live center spindle, and 9 the dead center carried by a bar 10, mounted in the tailstock 7 in axial alignment with the spindle 8 for end-wise sliding movement toward or from said spindle, and held where adjusted by a clamp 11.

Referring now in detail to the live center 12, the body 13 thereof is in the form of a truncated cone, having on its base at the axis thereof a hub 14 applied to the inner end of the spindle 8 to which it is rigidly but detachably secured by screw threads. In the face of the body 13 is a large relatively deep annular recess 15. Formed with body

13 within its recess 15, is a pair of diametrically opposite driving lugs 16. Also formed with the body 13, at the axis thereof and projecting into the recess 15, is a raised spherical bearing surface 17.

A piston X is shown held in the lathe by the centers 9 and 12, and which piston is provided with the customary internal bosses Y, which surround the seats therein for the wrist pin Z.

When the piston X is held by the centers 9 and 12, the outer edge of its skirt loosely bears against the conical bearing surface of the live center 12 and is held pressed there against by the dead center 9, the conical point of which extends into a seat therefor in the head of said piston. At the time the dead center 9 is brought into contact with the head of the piston X and said piston pressed against the conical bearing surface of the live center 12, said piston, by its loose contact with said conical bearing surface, will self-adjust itself thereon and be brought into true axial alignment with the axes of the centers 9 and 12.

To cause the piston X to rotate with the live center 12, said center is provided with a U-shaped driving dog 18 mounted in the recess 15 over the bearing surface 17 with its prongs extending outward thereof and is connected to the body 13 by a stud 20 which loosely extends through a relatively large hole in the hub 19 at the axis thereof. This stud 20 is mounted in a bore in the live center 12, at the axis thereof, rigidly secured thereto by a press fit and extends outward through the recess 15.

The driving dog 18 is detachably secured to the stud 20 by a friction lock 21 that comprises an annular lock groove in said stud and a spring pressed ball mounted in a seat in the driving dog 18 and extends into said lock groove. To hold the ball of the friction lock 21 in its seat when the driving dog 18 is removed from the stud 20 said seat is contracted. It is important to note, by reference to Fig. 4, that the position of the lock groove on the stud 20 is such that the friction ball, which is spring pressed therein, holds the hub 19 axially spaced from the

bearing surface 17. The loose connection between the hub 19 and stud 20 and the supporting of the hub 19 out of contact with the bearing surface 17 by the friction lock 21 ⁵ forms a wobbled joint between the driving dog 18 and the live center 12, which permits the driving dog 18 to rock on the stud 20, for a purpose that will presently appear. Under extreme rocking movements of the driving dog 18 on the stud 20 the same will engage the bearing surface 17.

The hub 19 of the driving dog 18 is substantially entirely within the recess 15, and extends between the driving lugs 16 for a limited pivotal movement, in respect thereto, about the axis of the stud 20 (see Fig. 3). The engagement of the driving lugs 16 with the driving dog 18 will drive said dog in the same direction with the live center 12. As ¹⁵ the connection between the driving dog 18 and the driving lugs 16 is loose, said connection does not interfere with the self-adjustment of the driving dog 18 in respect to the live center 12.

²⁰ When the piston X is held by the centers 9 and 12, the prongs of the driving dog 18 extend into said piston and straddle the wrist pin Z for contact with the bosses Y at opposite sides thereof, and form a connection between the live center 12 and piston X to cause said piston to turn with the live center 12.

²⁵ The purpose of the wobbled joint, between the driving dog 18 and live center 12, is to permit said dog to self-adjust itself in respect to the live center 12 so that both prongs of the driving dog 18 will engage the bosses Y. The necessity of this self-adjustment of the driving dog 18 in respect to the live center 12, is that the bosses Y are often out of axial alignment, uneven and vary in thickness and formation.

³⁰ The object of the recess 15 in the body 13 is to receive the transverse portion of the driving dog 18 and form a compact structure, and give as much clearance as possible between the stud 20 and wrist pin Z, for the reason that in certain pistons their wrist pins are relatively close to the outer edges of the skirts thereof and would interfere with the engagement of said skirt with the live center.

³⁵ From what has been said, it will be understood that the invention described is capable of modifications as to detail of construction and arrangement within the scope of the invention herein disclosed and claimed.

What we claim is:

⁴⁰ 1. In a device of the class described, a body having on its face a conical bearing surface, a recess in said face at the axis thereof, said body having in said recess a pair of diametrically opposite driving lugs, and a U-shaped driving dog, the transverse portion of which is mounted in said recess between the driving lugs with its outer face between the

prongs substantially in the same plane with the outer edge of said surface, and a wobbled joint connecting the driving dog to the body with freedom to turn about the axis thereof between the driving lugs. ⁷⁰

2. In a device of the class described, a body having on its face a conical bearing surface, a recess in said face at the axis thereof, and a U-shaped driving dog the transverse portion of which is mounted in said recess with its outer face between the prongs substantially in the same plane with the outer edge of said surface, and a wobble joint connecting the dog to the body. ⁷⁵

3. In a device of the class described, a body having on its face a conical bearing surface, a forwardly projecting fixed stud at its axis and a pair of diametrically opposite driving lugs, said stud being round in cross section and having intermediate of its ends a circumferentially extended annular lock groove, a U-shaped driving dog extending between the driving lugs and having at its axis a bore through which said stud extends and supports the driving dog with freedom to turn thereon between the driving lugs, and a spring-pressed friction member mounted on the driving dog and extending into the lock groove with freedom for circumferential movement therein, the diameter of the bore in the driving dog being of sufficient size to permit universal wobbling movement of the driving dog on the stud about the axis thereof, said lock groove and cooperating member being arranged to hold the driving dog on the stud spaced from the body to permit said wobble movement of the driving dog. ⁸⁰ ⁹⁰ ⁹⁵

4. The structure defined in claim 3 which further includes positive means, between the body and driving dog at the axis thereof, and arranged to prevent the driving dog from being forced axially against the body. ¹⁰⁰ ¹⁰⁵

5. In a device of the class described, a body having on its face a conical bearing surface, a recess in said face at the axis thereof, a bore at the axis of said recess, a boss on the body surrounding the bore and extending into the recess, a pair of diametrically opposite driving lugs in the recess and a fixed stud in the bore and extending into the recess, said stud being round in cross section and having intermediate of its ends a circumferentially extended annular groove, a U-shaped driving dog the transverse portion of which is mounted in said recess between the driving lugs, said driving dog having at its axis a bore through which the stud extends and supports the driving dog with freedom to turn thereon between the driving lugs, and a spring-pressed friction member mounted on the driving dog and extending into the lock groove with freedom for circumferential movement therein, the diameter of the bore in the driving dog being of sufficient size to permit universal wobbling movement of the ¹¹⁰ ¹¹⁵ ¹²⁰ ¹²⁵ ¹³⁰

driving dog on the stud about the axis thereof, said lock groove and cooperating member being arranged to hold the driving dog on the stud.

In testimony whereof we affix our signatures.

ADOLPH STORM.
THOR THORSEN.
